UNITED STATES PATENT OFFICE.

GARRETTSON SMITH AND HENRY BROWN, OF PHILADELPHIA, ASSIGNEES
TO ENOS S. SHANTZ AND OLIVER B. KEELEY, OF SPRING CITY, PA.

DESIGN FOR COOKING-STOVE.

Specification forming part of Design No. 6,701, dated June 10, 1873; application filed May 17, 1873.

To all whom it may concern:

Be it known that we, GARRETTSON SMITH and HENRY BROWN, of the city of Philadelphia, in the State of Pennsylvania, have invented a Design for the Doors of a Cooking-Stove, of which the following is a specification:

The nature of our design is fully represented in the accompanying engraving, to which reference is made.

A and B represent, respectively, the two front or fire doors; and C and D, the two side doors, respectively.

Our design consists in the ornamentations on the panels of the doors, each of the said panels being flat and supported by a broad edge-molding. The ornamentations on the doors A, B, and C, are substantially alike, and consist of a central shield, 1, surrounded by an oval wreath, 2, and a triangular orna-

ment, 3, in each of the four angles of the rectangular flat panel, surrounded by the molding of the door. The ornamentations on the oven-door D consist of the ornamented shield 4, surrounded by the oval wreath 5, and the triangular ornament 6, in each of the four angles of the rectangular flat panel, surrounded by the molding of the door.

The ornamentations specified are in bas-relief on the flat surface or face of the panel of the several doors.

What we claim as our invention is—

The ornamental design for the doors of a stove, substantially as described and shown.

GARRETTSON SMITH.
HENRY BROWN.
